LAUTER TUBS

Edwin L. Dittrich, East Orange, N. J., assignor, by mesne assignments, to The Pfaudler Co., Rochester, N. Y., a corporation of New York

Application November 9, 1953, Serial No. 390,890

6 Claims. (Cl. 259—108)

This invention relates to lauter tubs, and has for its object to provide several improvements thereto.

A lauter tub is essentially a device for straining wort liquid from the mash-grains; and comprises a perforated false bottom resting on and separated from the tank bottom itself by spacer studs attached to the false bottom. The tank bottom is provided with suitable drainage openings.

The invention provides a combined gear drive and hydraulic system unit motivating the shaft which revolves in a universal bearing attached to the bottom of the tank, said shaft having vertical freedom of movement through a central tank well.

The invention further provides a hydraulic system for changing the position of the lauter blades along their vertical axes by remote control.

The invention still further provides means for rotating the sparging unit which is hollow through its vertical axis to allow for free passage of feed lines.

The invention still further provides a flushout system which allows complete flushing of the tank bottom without lifting the false bottom.

The invention also provides lauter blades with strips of flexible material attached to their lower ends to allow said lauter blades to wipe the false bottom clear.

Finally, the invention provides a pneumatically operated spent grain valve.

The invention will be further described hereinafter, an embodiment thereof will be illustrated in the accompanying drawing, and the invention will be finally pointed out in the appended claims.

In the accompanying drawing:

Fig. 1 is a side elevation, partly in central vertical section of a valley bottom lauter tub assembly;

Fig. 2 is a top view of the valley bottom; taken on line 2—2 of Fig. 3;

Fig. 3 is a vertical section taken on line 3—3 of Fig. 2;

Fig. 4 is a section on line 4—4 of Fig. 2;

Fig. 5 is a section on line 5—5 of Fig. 2;

Fig. 6 is a section on line 6—6 of Fig. 2;

Fig. 7 is a side view of a detail of the channel knurling;

Fig. 8 is a top view of a removable channel section for clean out;

Fig. 9 is a side view of a channel section;

Fig. 10 is a section on line 10—10 of Fig. 9;

Fig. 11 is a detail view of tank shell;

Fig. 12 is an enlarged central vertical section of the hydro drive illustrated in Fig. 1;

Fig. 13 is an enlarged central vertical section through the self-aligning bearing and the lauter blades supporting system taken above the valley bottom;

Fig. 14 is an enlarged detail of a portion of the structure shown in Fig. 13, pointed out by the arrow;

Fig. 15 is a partial front view of a scraper type lauter blade;

Fig. 16 is a partial side view of the blade of Fig. 15;

2

Fig. 17 is a top view of the lauter blades actuating system;

Fig. 18 is a diagrammatic view illustrating various positions of lauter blades at end x—x of Fig. 17;

Fig. 19 is a section on line 19—19 of Fig. 2; and

Fig. 20 is a top plan view of portions of the drive mechanism shown in Figs. 1 and 12.

Similar characters of reference indicate corresponding parts throughout the various views.

Referring now in more detail to the drawing, and more particularly to Fig. 1, the tank 20 is circular and open at its top. A central rotating shaft 21 has arms 22 rigidly attached thereto and these arms 22 each supports a plurality of blades 23, the lower ends of which 15 are adjacent to the false bottom 24 which is open, is adjacent to and above the valley bottoms 25. These valley bottoms 25 are provided with discharge openings into pipes 26 which, in the embodiment shown are circular and all terminate in a parallel group of wort ring outlets 28 (Fig. 2). The flushout water inlet valves 29 (Fig. 2) are shown diametrically opposite. Such structures are known.

In conventional lauter tubs, the hydraulic cylinder is mounted into the interior of the tank and attached to the bottom itself. The purpose of the hydraulic cylinder is to enable the operator to impart vertical movement to the arms, to which are attached the lauter blades. In contrast to such conventional devices, the hydraulic cylinder 30 of my invention has been made an integral part of a newly designed gear drive unit and is completely removable from the lauter tank 20 itself. The actuating fluid employed in the new unit is oil, used in a suitable return system which permits continued re-use thereof. The use of the oil is very advantageous as it is conducive to smooth operation of the unit. The older lauter tub system necessarily had to use water as the hydraulic medium, so as to avoid contaminating wort with substances other than water.

The piston 49 of hydraulic cylinder 30 is aligned with 40 and rotatably connected to a splined shaft 48 capable of rotational movement by the gear drive while being at the same time movable in vertical direction by the action of cylinder 30, when desired. This drive may be a one-piece member, but the accompanying drawings illustrate it as a two-piece shaft connected by a rigid coupling.

The drive shaft 48 extends through the lauter tub tank bottom without packing glands, thus eliminating the glands commonly employed in prior constructions. In order to overcome the inherent difficulties experienced with such packing glands, provision has been made to eliminate the use of glands or stuffing boxes, as follows:

The shaft is aligned through a spherical universal bearing 32 and rotates in a bronze bearing sleeve which is non-rotatably mounted, but has sufficient movement 55 so that the bearing can turn to a limited extent in any direction about the center.

A stainless steel tube 63 of sufficient height to prevent any mash from slopping over the upper end and from eventually running out of the tub is attached to the top 60 of bearing 59 by a number of machine screws. This arrangement permits the drive shaft to extend through the mash, without the mash touching the shaft. Since the universal bearing is rigidly fixed to the tank bottom, it supports the shaft and the usual top outboard bearing 65 may be omitted.

The lauter arms, usually 2, 3, or 4 in number, are fastened to a hub 35 which in turn is attached to the vertical drive shaft by means of a tight keyed fit with bronze bushing.

It is customary that each of the lauter arms be provided with some sort of mechanism to rotate the lauter blades about their vertical axes. Usually this motion

is instituted through a worm gear assembly and suitable linkage to each lauter blade, each lauter arm being provided with its individual worm gear mechanism. This usually entails considerable time and physical effort by the operator. In the improvement according to this invention, the worm gear mechanism has been replaced by a hydraulic double acting cylinder, which in turn, through proper linkages, actuates the individual lauter blades. Whether the tub has two or more lauter arms, one hydraulic cylinder is used.

The hydraulic system required for operation of the sparger acts in the following manner:

The liquid which in this case will be water is conducted by copper tubing to the rigid pipe 67 which is fastened to the top of the shaft 48, so that it moves with the shaft. To the top of the piping is fitted a liquid-tight coupling 68, with one member of the coupling rotating about the other. Since the rigid vertical pipe must move in a vertical direction with shaft 48, a flexible hose 70, 71 is used to connect the non-rotating coupling to the shell of the lauter tub.

Another improvement is in passing the hydraulic piping through the rotary sparger.

Still another improvement is in a flushout system, in which the lauter tank bottom can be cleaned without raising the false bottom. Previous efforts were made to accomplish this function by using ordinary spray nozzles, but the coverage was never complete.

By the use of an inverted channel, whose flanges are serrated, tack welded to the tank bottom in an inverted position, a thin film of water at high velocity sweeps the bottom of the tank clean. Water is conducted to the channels at various points by a manifold system.

It has been a continual problem in the industry to effect the removal of the last 1" or 1/2" of grains laying on the false bottom. The spent grains were removed by the lauter blades which have been turned sidewise. To prevent digging in and ripping up the false bottom, the lauter blades were never allowed to descend closer than a predetermined distance. The brewer then either had to shovel or sweep out the residual grains with manual labor. Or, he would lay a piece of hose belting or plank in front of the blades, and riding the false bottom.

In the improved lauter blade, a section of flexible material (such as a synthetic or natural polymer, or the like) is inserted in the bottom of the lauter blade. The presence of the polymer does not interfere with the normal function of the blade. However, when the blades are used for removing grains, it becomes possible to lower the blades to a point where there is actual physical contact of the flexible scraper with the false bottom. The polymer being flexible, there is no danger of damaging the false bottom, since the flexible material merely acts as a "sweeper."

It has also been customary to operate the spent grains valve, which is in effect a sliding valve, manually. In accordance with this invention, design has been changed to allow the valve to function with a double acting pneumatic cylinder. A ledge has been incorporated in the valve body serving as a further support for the valve stem.

A pump 38 supplies the high pressure oil to actuate the hydraulic ram 30, by pipe 30a, through a check valve 39, a by-pass line 40 being provided to return the oil from the cylinder to the pump reservoir 41. This by-pass has a solenoid valve 42, and an adjustable valve 43. A push button 44 for the motor 38a is provided. The by-pass 40 leads into the tank 41. A pump inlet filter 46 is shown. On the panel board (not shown) a device 47 with limit switches, is used, whereby the travel of the main shaft 48 of the lauter machine may be predetermined. The piston 49 of the cylinder supports the shaft 48 which leads to the compression coupling 50. The lower part of the shaft 48 is splined as at 51, to engage it with the spider 52. The spider carries the low

speed worm gear 53. The high speed worm 110 has a double expanded shaft on the right hand side 111 being connected with a flexible coupling 54 of a large moving rotor motor 55. The left hand side 112 is connected with the free wheeling coupling 56, which is connected with a triple reduction gear motor 57. When the high speed motor 55 is energized while putting the mash into the tub and also when removing spent grains, free wheeling coupling 56 allows the low speed, reduction gear motor 57 to remain at rest, but the high speed worm 110 on shaft 111 drives a worm gear 113 which drives a shaft 114 carrying a worm 115 which, in turn, drives low speed worm gear 53. When low speed motor 57 is energized as in lautering off, it drives shaft 112 and worm 110 and, through the connection described, drives worm 53 at a lower speed, shaft 111 being merely idled in its motor 55.

The arrow 58 shows the direction of rotation. The upper end of the shaft 48 is supported by a self aligning sleeve bearing 59, comprising a spherical member 60 enclosed by a split bearing housing 61 (in two parts Fig. 13), whose lower flanged end 62 is fastened to valley bottom 25. The false bottom 24 rests on said flange 62.

The object of this self aligning bearing is to overcome any bending of the shaft 48 in the event that the lauter tank tilts, either by underbalanced load, or other reasons, as uneven support or settlement in the brewing.

No stuffing box is needed as the shaft 48 is surrounded by a telescopic sleeve 63, the upper end of which is well over the liquid level at all times. This sleeve surrounds shaft 48 and is connected by bolting to the top of the self aligning bearing 59. An apron 64 concentrically surrounds said sleeve 63 and is fastened to a support 65 which carries the lauter arms 22. When the support 65 is raised the apron 64 serves to prevent liquid from splashing onto the shaft 48.

At the top of the shaft 48 is an inset 66, which has the series of ducts shown in Fig. 14 illustrating a detail of Fig. 13.

A tubular member 67 extends upwardly through a sparger unit 68 into a rotary union 69, through a flexible hose connection 70, to a valve and hydraulic pump on the outside of the tank, and another hose connection 71 from the pump and valve shown in Fig. 1.

The insert 66 has one duct and connection 72 which discharges into one side of the hydraulic cylinder 73, while the other side of the hydraulic cylinder is connected with a duct and connection 74.

When the hydraulic cylinder 73 is actuated, its piston actuates one end of an elbow lever 75, which is pivoted at 76. The other end of the elbow lever 75 is connected with a link 77 in turn pivoted to a lever 78 which actuates the blade linkage so as to move the blades irregularly. A similar connection with link 79 and lever 80 connects the operation of the elbow lever to the blade linkage of the second arm 22. The blade linkage of the third arm 22 is connected with and operated by lever 75, as shown.

From the operation of the blade control described, the blades take different positions as shown in diagrammatic form in Fig. 18, illustrating the last five blades at the free end of arm 22, as indicated at x-x in Fig. 17.

The lower ends of the blades are provided with an insert 81 of polymer, or any other flexible material. This is flexible and in closing the space from the blades to the false bottom, an efficient clearing of the false bottom of the grains is provided. (Figs. 15 and 16.)

To remove the spent grains, the valley bottom and the false bottom are provided with registering openings. A valve cover 82 closes normally the openings, or more particularly the lower opening. A support 83 is provided for a shaft 84 which has a clamp 85 against which a forked lever 86 acts to push the valve cover 82 upwardly so that the gasket 87 is compressed to form a tight seal. An air cylinder 88 is connected with the

end of the shaft, so that on the operation of air cylinder the shaft 84 is drawn toward it. This removes the valve cover 82, and permits the contents to descend through the openings into the discharge chute 89.

In the use of lauter tanks, and the grinding of the grains of the malt while the wort drains through the false bottom, a quantity of "sludge" or "overdough" known also as "underdough" is formed on the valley bottom. To remove these, it was usual to lift up the false bottom segment, and this was cumbersome. This improvement comprises providing a supply of rinsing water at the distributing pipes, so that the sludge or overdough is washed away.

The main body of such pipes is easily supplied, but the outer and inner radial parts of the pipes need some modification.

In Fig. 2 there is shown in plan view a series of supply pipes 90, terminating at the circular pipes 91, 92 and 93 and 94 and controlled by valves 29. The pipes 26 in Fig. 3 are the known wort collecting pipes, and the pipes 91 to 94 are the water supply pipes.

In Fig. 4, this pipe 92 extends upwardly to below an opening 98 in the valley bottom. This opening 98 is covered by a channel 99, the flanges of which have serrations or ragged edges as shown in Fig. 7, for the purpose of evenly distributing the flush water so it acts to remove the sludge evenly throughout. The false bottom has an angular member 100 to rest on the channel 99, and the channel 99 is circular and formed in concentric dispositions corresponding to the high spots of the valley bottom. The channel 99 is free to discharge at both sides and is tack welded to the valley bottom high spot as at 101. This form of channel 99 is of the type supplied by pipes 92 and 93. The channel supplied by pipe 94 alongside the tank shell at the outermost side, flushes out only at the inside leg of the channel (Fig. 5). The channel is continuously welded at 101a.

In Fig. 6, the innermost portion of the tank is shown, where the pipe 91 feeds the channel which in this case is formed by a cutout 99a, and a ring 102 held by a screw 103. Here as radially outward, one side of the valley is flushed.

In the cleaning of the channels, it is advisable to cut out a part of the channel, and then clean from the openings inwardly into the channel. When this has been done, then the cut out section is replaced and held by spring clamps in place. This is shown in Figs. 8, 9, 10 and 11.

While I have described the novel features of the present invention in connection with one preferred embodiment thereof, obvious modifications may occur to a man skilled in the art and I therefore do not desire to be limited to the exact details shown but only by the scope of the appended claims.

I claim:

1. A lauter tank having a valley bottom and a false bottom spaced above said valley bottom, a shaft projecting upwardly into said tank through said bottoms, lower bearing means for said shaft below said tank bottoms, a self-aligning bearing for said shaft in substantially horizontal alinement with said false bottom and in vertical alinement with said lower bearing means, whereby said shaft is relieved of bending stresses and free of supporting bearings above said self-aligning bearing, means operatively engaging said shaft below said bottoms for rotating and moving the same vertically in said bearings, means on said shaft having a plurality of radially extending lauter arms, a plurality of blades pivotally supported by and depending from said lauter arms, a device on said lauter arm means including motor means for rotating said blades, and remote control means for said motor means located on the outside of said tank.

5 2. A lauter tank having a valley bottom and a false bottom spaced above said valley bottom, a shaft projecting upwardly into said tank through said bottoms, lower bearing means for said shaft below said tank bottoms, a self-aligning bearing for said shaft in substantially horizontal alinement with said false bottom and in vertical alinement with said lower bearing means whereby said shaft is relieved of bending stresses and free of supporting bearings above said self-aligning bearing, means operatively engaging said shaft below said bottoms for rotating and moving the same vertically in said bearings, means on said shaft having a plurality of radially extending lauter arms, a plurality of blades rotatably supported by and depending from said lauter arms, a device including motor means on said lauter arm means for rotating said blades, a tubular extension on said shaft above said lauter arm means, and remote control means for said motor means connected through said shaft extension and located on the outside of said tank.

10 3. A lauter tank having a valley bottom and a false bottom spaced above said valley bottom, a shaft projecting upwardly into said tank through said bottoms, bearing means for said shaft, means operatively engaging said shaft below said bottoms for rotating and moving the same vertically in said bearing means, means on said shaft having a plurality of radially extending lauter arms, a plurality of blades rotatably supported by and depending from said arms, a device on said lauter arm means for rotating said blades, a hollow extension on said shaft above said lauter arm means, and remote control means for said device connected therewith through said shaft extension and located on the outside of said tank.

15 4. A lauter tank having a valley bottom and a false bottom spaced above said valley bottom, a shaft projecting upwardly into said tank through said bottoms, lower bearing means for said shaft below said tank bottoms, a self-aligning bearing for said shaft in substantially horizontal alinement with said false bottom and in vertical alinement with said lower bearing means whereby said shaft is relieved of bending stresses and free of supporting bearings above said self-aligning bearing, means operatively engaging said shaft below said bottoms for rotating and moving the same vertically in said bearings, means on said shaft having a plurality of radially extending lauter arms, a sleeve on said self-aligning bearing enclosing said shaft to an elevation above the liquid level in said tank, and an apron sleeve depending from said lauter arm means and telescopically and slidably engaging said 20 first mentioned sleeve to prevent access of liquid to said self-aligning bearing.

25 5. A lauter tank having a valley bottom and a false bottom spaced above said valley bottom, a shaft projecting upwardly into said tank through said bottoms, lower bearing means for said shaft below said tank bottoms, a self-aligning bearing for said shaft in substantially horizontal alinement with said false bottom and in vertical alinement with said lower bearing means whereby said shaft is relieved of bending stresses and free of supporting bearings above said self-aligning bearing, means operatively engaging said shaft below said bottoms for rotating and moving the same vertically in said bearings, means on said shaft having a plurality of radially extending lauter arms, a plurality of blades rotatably supported by and depending from said lauter arms, a device on said lauter arms including motor means for rotating said blades, remote control means for said motor means located on the outside of said tank, a sleeve on said self-aligning bearing enclosing said shaft to an elevation above the liquid level in said tank, and an apron sleeve depending from said lauter arm means and telescopically and slidably engaging said first mentioned sleeve to prevent access of liquid to said self-aligning bearing.

30 6. A lauter tank having a valley bottom and a false

bottom spaced above said valley bottom, a shaft projecting upwardly into said tank through said bottoms, bearing means for said shaft, means operatively engaging said shaft below said bottoms for rotating and moving the same vertically in said bearing means, means on said shaft having a plurality of radially extending lauter arms, a plurality of blades rotatably supported by and depending from said lauter arms, a device on said lauter arms including motor means for rotating said blades, a tubular extension on said shaft above said lauter arm means, remote control means connected with said motor means through said tubular extension and located on the outside of said tank, a sleeve connected with said false bottom and enclosing said shaft to an elevation above the liquid level in said tank and an apron sleeve depending from 15 said lauter arm means and telescopically and slidably engaging said first mentioned sleeve to exclude liquid from said shaft.
